UNITED STATES PATENT OFFICE.

EDWIN L. HARMON AND OTTO PETERMANN, OF GROTON, NEW YORK, ASSIGNEES TO CORONA TYPEWRITER COMPANY, INC., OF GROTON, NEW YORK, A CORPORATION OF NEW YORK.

TYPEWRITING MACHINE.

Application filed September 10, 1919, Serial No. 322,774. Renewed January 15, 1923.

To all whom it may concern:

Be it known that we, EDWIN L. HARMON, a citizen of the United States, and OTTO PETERMANN, also a citizen of the United States, both residing in Groton, county of Tompkins, and State of New York, have invented new and useful Improvements in Typewriting Machines, of which the following is a full and clear specification.

10 The object of this invention is to improve and simplify the type-bar action, as more fully hereinafter set forth.

In the drawings—

Fig. 1 is a vertical longitudinal sectional view of so much of a typewriting machine as is necessary to illustrate our present invention;

15 Fig. 2 is a front elevation thereof, partly broken away;

20 Fig. 3 is a detail vertical sectional view taken through the pivot of one of the bell-cranks or sub-levers.

Referring to the drawings annexed by reference characters, 10 designates the usual sheet-metal key-levers which are pivoted at their rear extremities to a transverse fulcrum-bar 11, the pivotal connections being provided by vertically slitting the bar 11 and providing each key-lever with a hook-like extremity 12 engaging in one of the slots, said slots being grouped according to the grouping of the key-levers and being closed at their upper ends as well as at their lower ends so as to thereby avoid the necessity of using pivot-pins. It will be understood that suitable springs, as 27, will be used for normally holding up the key-levers; and it will be also understood that fulcrum-bar 11 will extend substantially entirely across the machine and be rigidly attached to the frame thereof. It will be understood also that this fulcrum-bar will serve for the spacing-levers and case-shift-levers as well as the aforesaid key-levers.

45 At a point between the fulcrum-bar 11 and the key-ends of the key-levers, these flat key-levers are spaced and vertically guided by a slotted plate 13 which at its ends is rigidly affixed to the side-walls of the frame. The slots are, of course, in fore-and-aft alinement with the slots in the fulcrum-bar 11 so as to cooperate therewith in accurately guiding the levers in their verti-

cal movement. This comb-plate 13 is bent longitudinally at two points 14 and 15 to 55 form a shelf 16 extending substantially entirely across the machine, the forward edge of this shelf extending upwardly to serve as a flange-like support 17 for the bell-cranks or sub-levers 18, said flange 17 increasing in height from the center of the machine outwardly to provide an arcuate support for said bell-cranks 18.

A stop-bar 19 is affixed to the front face of the flange 17 to restrict the upward movement of the key levers, and each key-lever is connected to the forward end of its companion bell-crank 18 by means of a pivotal link 20, the other end of the bell-crank being connected to the type-bar as usual by a 70 link 21. The link 20 is connected to the key-lever through the medium of a forwardly-extending ear 22 formed integral with the upstanding part of the key-lever, this ear 22 being bendable laterally as well 75 as slightly up-and-down to permit such adjustments to be made as will enable the link 20 to work with a minimum of friction and at the same time impart to the type-bar the desired movement. In this 80 way we avoid the use of a turn-buckle or other adjusting screws in the connection between the key-lever and the bell-crank.

The manner of supporting the bell-cranks on the upper edge of the flange 17 consists 85 in vertically slitting the upper part of said flange to form upstanding ears 23 and then twisting each ear to different angles, so as to bring its vertical flat faces in parallelism with the slots of the segment. Each ear is 90 provided at its upper end with a hole for the reception of the bell-crank pivot 24, this pivot being formed integral with the bell-crank by laterally displacing the metal thereof, as shown in Fig. 3. To hold each 95 bell-crank to its ear 23, with its pivot properly in place, we provide each bell-crank with an ear 25 springing from the upper edge of the bell-crank and bending over and downwardly upon the opposite face 100 of the ear 23, the front end of this ear 25 lying lightly against the adjacent face of the ear 23 and coming into contact (or nearly into contact) with the end of the integral pivot 24. In this way a very 105 simple pivotal connection is provided be-

tween the bell-crank and the upstanding ear of the comb-plate; a connection which avoids the use of separate pivots or adjustment screws.

5 Affixed, desirably by spot-welding, to the shelf 16 is an upstanding flange 26 whose upper edge is curved to correspond with the arcuate arrangement of the bell-crank-levers 18, the extreme upper edge of this flange 10 being provided with holes at intervals to receive the lower rear ends of the light coil-springs 27 whose upper ends are connected to the bell-crank-levers to hold the type bars and key levers in normal position. This 15 arrangement affords a very simple and compact as well as easily-assembled mechanism for maintaining the same tension on all the type-bar actions irrespective of position in the type-basket, and a feature of special importance is that the springs 27 are not only of minimum length but are all of uniform length. A feature of special importance lies in combining the key-lever comb-plate 13, the fulcrum-support for the bell-cranks and 20 the anchorage of the tension-springs 27 in a unitary structure, thereby tending to economy in manufacture as well as ease and accuracy in assembling.

The ends of the upstanding part 17 of the 30 combined comb and fulcrum supporting plate are each provided with a rearwardly-extending flange 28 which is fastened by suitable screws 29 to the inner faces of the side-walls of the frame, and this anchorage 35 to the side-walls is a very substantial one in view of the fact that at the points of anchorage this plate has a considerable width due to the fact that the fulcrum flange 17 increases in width toward the end of the plate. 40 It will be observed that all the parts mounted on this combined comb and fulcrum plate will be assembled thereon before it is fastened in the machine frame, thereby contributing greatly to ease of assembling, and 45 by reason of the fact that the key-lever-comb and the bell-crank-supporting-ears are formed upon a single plate accuracy in manufacture and adjustment will be materially promoted.

50 The nature and scope of the invention having been thus indicated and its preferred embodiment having been specifically described, what is claimed as new is:

1. A combined key-lever guide and sub-lever support for type-bar actions comprising a metal plate having a downwardly bent portion slotted vertically at intervals to form a key-lever guide comb and having an upwardly bent portion provided with pivot 55 ears for the sub-levers of a type-bar action.

2. A combined key-lever guide and sub-lever support for type-bar actions comprising a plate having a depending flange at one end slotted vertically at intervals to 60 form a key-lever guide comb and having an

upstanding flange at its other edge, said upstanding flange being provided with integral upstanding ears along its upper edge twisted at an angle to the plane of the flange to form sub-lever supports.

3. In a typewriting machine, a combined comb-plate and a bell-crank-lever-support consisting of a single plate bent downwardly to form a comb at its rear edge and bent upwardly at its forward edge to form a support for the bell-cranks.

4. In a typewriting machine, a plate extending across the machine and anchored rigidly to the side walls thereof, said plate having one edge bent downwardly and provided with slots to form a key-lever-comb and its other edge bent upwardly to form a support for the sub-levers of the type-bar action.

5. In a typewriting machine, a plate extending across the machine and anchored rigidly to the side walls thereof, said plate having one edge bent downwardly and provided with slots to form a key-lever-comb and its other edge bent upwardly to form a support for the sub-levers of the type-bar action, and an anchorage flange for the springs of the type-bar action fastened to an intermediate point on said plate.

6. In a typewriting machine, a main frame, and a sheet metal plate, extending transversely of the frame and rigidly held thereto, said plate having a downwardly bent portion and an upwardly bent portion extending transversely of the frame, the downwardly bent portion being provided with a series of vertical key-lever-guide slots, and said upwardly bent portion gradually increasing in height from the middle to the ends thereof and being provided with an arcuate series of integral upstanding pivot lugs twisted into planes at an angle to the upwardly bent portion of the plate for supporting the sub-levers of a type-bar action.

7. In a typewriting machine, a transverse plate anchored to the frame of the machine at its ends and bent transversely to form a front upstanding flange and a rear downwardly turned flange formed into a key-lever-comb, the intermediate part forming a shelf, bell-crank-levers of the type-bar action supported on said upstanding flange, said upstanding flange having an arcuate curvature, an anchorage flange fastened to said shelf and having its upstanding edge conforming to the arcuate arrangement of the bell-crank-support, and springs connecting the bell-cranks to the curved upper edge of said flange.

8. A type-bar action assembly unit comprising a key-lever guide comb, a key-lever stop bar carried by the comb, and a support for sub-levers carried by the comb.

9. A type-bar action assembly unit comprising a key-lever guide comb, sub-lever

supporting means carried by the comb, and anchoring means for sub-lever return springs carried by the comb.

10. A key-lever guide comb and sub-lever

5 support comprising a plate having a depending flange provided with key-lever guide slots and an upstanding flange provided with pivot ears for supporting the sub-levers of a type-bar action, and an angular member having one web secured to the upper side of said plate and an upstanding web provided with apertures for receiving the ends of return springs for the sub-levers.

15 11. A type-bar action assembly comprising a key-lever guide comb, a key-lever stop bar carried by the comb, upstanding sub-lever supports carried by the comb, and an anchoring member for sub-lever return springs carried by the comb.

20 12. In a typewriting machine, the combination of a frame, a type-bar segment supported in the frame, a plate extending transversely of the frame forward of the segment and rigidly supported in the frame, 25 a flange depending from the rear edge of said plate provided with key lever guide slots, a flange extending upwardly from the forward edge of said plate and provided with an arcuate series of ears twisted laterally, sub-levers pivotally held to said ears, key levers extending through the slots in the depending flange and fulcrumed in the frame, links connecting the key levers with the sub-levers, and links connecting the sub-levers with the type bars.

30 13. In a typewriting machine, the combination of a frame, a type-bar segment supported in the frame, a plate extending transversely of the frame forward of the segment and rigidly supported in the frame, 35 a flange depending from the rear edge of

said plate provided with key lever guide slots, a flange extending upwardly from the forward edge of said plate and provided with an arcuate series of ears twisted laterally, sub-levers pivotally held to said ears, key levers extending through the slots in the depending flange and fulcrumed in the frame, an upstanding anchoring member held to said plate adjacent the rear edge of the plate and having an arcuate upper edge, 45 springs connecting the sub-levers with the upper edge of said member, links connecting the key-levers with the sub-levers, and links connecting the sub-levers with the type-bars.

14. In a typewriting machine, the combination of a frame, a type-bar segment supported in the frame, a plate extending transversely of the frame forward of the segment and rigidly supported in the frame, a flange depending from the rear edge of said plate provided with key lever guide slots, a flange extending upwardly from the forward edge of said plate and provided with an arcuate series of ears twisted laterally, sub-levers pivotally held to said ears, key levers extending through the slots in the depending flange and fulcrumed in the frame, links connecting the key levers with the forward ends of the sub-levers, means connecting the rear ends of the sub-levers with the type-bars, an upstanding anchoring member held to the plate, springs connecting the sub-levers with said member, and 60 a key-lever stop bar held to the forward face of the upwardly extending flange on the plate and extending over the key levers.

This specification signed this 30th day of August, A. D. 1919.

EDWIN L. HARMON.
OTTO PETERMANN.
